UNITED STATES PATENT OFFICE.

MILLARD VON HALLE, OF PALISADES PARK, NEW JERSEY, ASSIGNOR TO THE STANDARD CORSET COMPANY, OF NEW YORK, N. Y., A CORPORATION OF MASSACHUSETTS.

BONING FOR FLEXIBLE MATERIALS.

Application filed November 16, 1926. Serial No. 148 625.

This invention relates to a boning or reinforcement for flexible material and is particularly applicable to garments, such as corsets, girdles, abdominal and surgical belts, and the like.

It has heretofore been the custom to effect boning of such garments by means of narrow strips of material, such for instance as whalebone, placed vertically or diagonally in or across the garment. This method of boning has many disadvantages, as, for instance, the ends of these reinforcing strips quickly wear or cut through the material and have a tendency to "dig" into the body of the wearer; and, if these strips are not possessed of sufficient resilience to come back to normal position in response to the movements of the wearer of the garment, the shape of the garment becomes distorted or the strips break causing much discomfort to the wearer, while, if possessed of sufficient resilience to react from the bending caused by the movements of the wearer, they are very likely not to have sufficient rigidity to meet many of the requirements of such garments.

The invention of this application obviates these disadvantages by providing boning or reinforcement that is flexible, adaptable and durable and capable of providing a greater degree and distribution of strength and pressure where these are needed than are the method and means now in general use. These results are attained by the use of a plurality of plates or disks of material of considerably greater rigidity than the material to be reinforced, flexibility being obtained by the arrangement of these disks or plates in the garment.

The invention is herein disclosed in a preferred and concrete form, applied to a body support, in the following drawings in which

Fig. 1 is a fragmentary view in side elevation of an abdominal belt showing the plates applied to the garment in a single vertical row;

Fig. 2 is a plan view of one of these plates removed from the garment;

Fig. 3 is a cross sectional view, taken at the line 3-3 of Fig. 1, of one of the plates when applied to the garment; and

Fig. 4 is a similar view to Fig. 1 showing

a double row of plates or disks in staggered relation.

Many other embodiments of the invention are possible and the plates may be made in a great variety of shapes and sizes; arranged in many different relations to each other; and of any material of sufficient rigidity.

In Figs. 1 and 3 of the drawings, the abdominal belt or support is of ordinary character having the usual fastenings 1, lacings 2, elastic inserts 3, stitchings 4, etc., all of which have no bearing on this invention and that part 5 of the garment to be boned or reinforced is made as usual of a double layer of flexible material 6.

In the embodiment of the invention here disclosed, the plates are in the form of thin flat disks 7 preferably of rigid material such as a fine grade of magnetized steel which is strong and admits of the disks being made very thin without impairment of their strength and therefore does not increase materially either the weight or bulk of the garment.

As shown in Fig. 1, the disks 7 are arranged in a vertical row in spaced fixed relation to each other between the layers of flexible material 6; and each of the disks 7 is provided with a central aperture 8 for the reception of an eyelet 9 that also passes through corresponding apertures 10, in the adjacent layers of flexible material 6, that register with the central aperture 8 of the disk. The edges of apertures 10 in the flexible material 6 are engaged by the flanges of the eyelet 9 when it is compressed into fastening position after it has passed simultaneously through the aperture 8 of the disk and the apertures 10 of the adjacent layers of flexible material and thus secures the disks to the flexible material. The layers of flexible material 6 are then stitched together adjacent to and circumferentially of each disk 7 to confine the disks and hold them in fixed relation to each other.

In Fig. 4 is shown a modification of the arrangement of disks 7, there being two vertical rows of these disks, the disks being in fixed staggered relation to each other to prevent bends and breaks along horizontal lines as might occur if the adjacent disks of the two

rows were in opposed relation to each other.

It is obvious that numerous other arrangements of the disks in respect to their relation to each other may be made to meet particular requirements; and that any suitable means may be employed to secure the plates or disks to the flexible material and to confine them in fixed position between the layers of flexible material.

10 It will also be obvious that this boning and reinforcing is very much more adaptable to various conditions than are those heretofore used since it admits of greater distribution of pressure, greater strength at particular and desired points and greater flexibility and comfort. With this invention, the strains radiate in all directions from the center of the plates or disks thus distributing the pressure over a greater area when desired; and a very much stronger garment is produced where the stitching confining the plate extends around in all directions so that the strains and pulls upon it are neutralized because they lie in different planes than is the case of stitching along the sides of strips in which case the strains and pulls are all in the same plane and hence have a tendency to weaken. Therefore, the more boning, the more stitching and greater weakening effect.

30 This invention admits (1) of greater variations in the degree of flexibility or rigidity than has heretofore been possible as they may be achieved by variations in the size of the plates or disks, their arrangement and their 35 distance from each other; (2) of greater comfort because there are no sharp and protruding ends; (3) and of greater durability because the plates will not cut through the fabric nor break under stress, there being a

greater distribution of strain than is possible with a narrow strip.

The term garment as used in this specification and the accompanying claims is intended to mean any article of wearing apparel whether it be for medical or surgical purposes, such as abdominal belts and other body supports, or an article to be worn as an outer garment or to be worn as an under garment.

I claim:

1. A boning for a garment made of layers of flexible material comprising: a plurality of plates of greater rigidity than and interposed in spaced relation between the layers of flexible material to resist strains at a plurality of points on said flexible material when under tension, means for securing each plate and the adjacent portions of the layers of flexible material together at the center of each plate to sustain the strains on said flexible material at that point, and means adjacent and surrounding the outer edge of each plate individually for confining it within a given area to distribute the strains on the flexible material and thereby to relieve the strain at the center of the plate.

2. As a new article of manufacture: superposed layers of flexible material, a disk interposed between the layers of material, and means securing the disk and layers together comprising: an eyelet at the center of the disk clamping the flexible material to the disk and stitching passing through the layers of flexible material and circumferentially surrounding the disk.

Signed in the borough of Manhattan, city, county and State of New York, this 10th day of November, 1926.

MILLARD VON HALLE.
